UNITED STATES PATENT OFFICE.

CHARLES WARREN, OF GUELPH, CANADA, ASSIGNOR TO THE BELL ORGAN AND PIANO COMPANY, LIMITED, OF GUELPH, ONTARIO, CANADA, A CORPORATION.

MOTOR FOR SELF-PLAYING ORGANS.

SPECIFICATION forming part of Letters Patent No. 737,180, dated August 25, 1903.

Application filed May 10, 1901. Serial No. 59,674. (No model.)

To all whom it may concern:

Be it known that I, CHARLES WARREN, musical-instrument expert, of the city of Guelph, in the county of Wellington, in the Province of Ontario, Canada, have invented certain new and useful Improvements in Motors for Self-Playing Organs, of which the following is a specification.

My invention relates to that class of pneumatic organs which may be played either from the ordinary keyboard or automatically by means of a tracker-board and perforated music-sheet; and the object of the invention is to simplify, cheapen, and make the construction of such instrument more compact, avoid the liability of its being affected by climatic changes, and the consequent liability to get out of order under such conditions; to enable the instrument to be used for ordinary playing without disturbing the position of the mechanism nor necessitating the covering of the tracker-board, as is required in other constructions, and to provide a silent and practically frictionless means of blowing or exhausting the feeders or reservoir, or, in other words, an improved motor for automatically playing in which the valves will not be liable to be influenced by climatic changes.

In order that the invention may be fully understood, I will describe the same by reference to the accompanying drawings, in which—

Figure 1 is a general perspective view of the exterior of my organ, showing the casing broken away to exhibit generally the parts involved in my invention. Fig. 2 is a side elevation attached to a rewinding mechanism. Fig. 3 is an inverted plan of the pneumatics and showing their relation to the key-levers. Fig. 4 is a sectional side elevation of an arrangement for operating the exhaust-feeders.

In carrying out my invention I employ a vacuum-chamber *a*, extending longitudinally and communicating with the tracker-board *b* by tubes *c*, communicating alternately with diaphragms *d* in the front and back walls of the vacuum-chamber; valves *e*, covering openings *e'*, connecting the chamber *a* with the outer air, being adapted to be operated by the diaphragms *d* in the usual well-known manner.

The vacuum-chamber is provided with pneumatics *f* on its under side placed end to end in two rows, one row being somewhat in advance of the other, so that the end of a pneumatic in one row is opposite the ends of two pneumatics in the other row. By this construction each pneumatic *f* is directly over its particular key-lever *f'*, to which it is connected by a string *g* or its equivalent. The keys are independently connected with operating mechanism of the ordinary type and are provided with a jumper-rail *f''* above their pivots *f'''* to prevent them being lifted at this point when operated by the pneumatics *f*.

I shall now describe the mechanism of the motor whereby the music-roll is driven, so as to coact with the tracker-board, and whereby also the said roll is rewound.

A is the trunk, leading from the exhaust-chamber *B* to above the plate *C*, upon the bottom of which the pneumatics 1, 2, and 3 are connected. The trunk *A*, as will be seen, extends upwardly and communicates with the casing *A'*, which is supported at the rear end of the plate *C*. The partition *A'*, substantially L-shaped in cross-section, extends through the casing *A'*, dividing it into two portions and forming one of the seats for the double-acting valves *D*. Each double-acting valve *D* has a valve-rod *D'*, which at the upper end extends through a nut or button *D''*. The valve-rods *D'* extend at the top through a hole *E* and at the bottom through a hole *E'*, the hole *E* being designed to admit the air and the hole *E'* communicating with the vacuum and exhaust chamber *B*. The valve-rod *D'* is supported at the top and bottom in suitable guiding-fingers *D'''*. It will be seen that there are three pneumatics, corresponding to the number of the valves, and their connections to such valves are as follows: Each pneumatic has secured on the bottom thereof the bars 1', 2', and 3', which are connected by the connecting-bars 1'', 2'', and 3'' to the cranks 4', 4'', and 4''' of the motor-spindle 4. These cranks are of course differently set in relation to each other, as indicated, and the motor-spindle 4 is journaled in suitable bearings 5.

6, 7, and 8 are levers pivoted on the bearing-brackets 9 and having one end extending underneath the cams 6', 7', and 8'. The other

ends have spring-fingers 10, which extend under the nuts or buttons D² on the valve-rod D', such spring-fingers having a limited vertical play.

5 I shall now describe the means whereby a continuous regular motion is imparted to the motor-spindle.

When the double-acting valve D is lifted by its cam 7' and the lever 7, the corresponding pneumatic is collapsed and motion is imparted to the crank 4². Upon the cam 7' releasing the lever 7 the corresponding valve D returns to its normal position, and the air is admitted through the opening E. As there are three pneumatics, a constant exhaust or vacuum is acting, for the reason that the other cranks are operated in rotation, thus insuring a complete and continuous revolution. Of course I may dispense with one of the pneumatics and its corresponding mechanism; but I prefer the three to obtain the best results.

15 The valve N' serves to create a vacuum in the motor when the opening which it covers is open or to render the motor inoperative 25 when the valve is closed and the instrument played manually. This valve N' is connected by the rod N² to an upright N³, which in turn is connected by the link N⁴ to the crank-rod N⁵, which extends into a slotted block N⁶, connected to the stop N.

30 It will be understood that j indicates the exhaust-feeder, and j' the pneumatic, operated in one direction by spring y and in the other direction by straps v, connected by rods 35 w to the pedal x, this being a simple and convenient form of operating mechanism.

What I claim as my invention is—

1. The combination with the motor pneumatics and spindle and suitable valves for

the pneumatics, of the exhaust-chamber and 40 the trunk communicating with the valves of the pneumatics a cross-wall in the trunk having an opening therein, and a suitable valve for closing said opening, a rod connected to the valve and provided with suitable connecting-links at the outside of the trunk, a stop provided with a slotted block and a crank-rod suitably journaled and having one end extending through the slot in the block on the stop and the other end pivotally connected to the link as and for the purpose specified.

2. The combination with the motor-spindle and the driving connection from the same to the music-winding drum and the rewinding- 55 roller, of the vacuum-chamber and the cross-casing and a plurality of pneumatics situated beneath such casing, an L-shaped cross-wall extending from end to end of such casing, an opening in the horizontal portion of such 60 cross-wall and an opening directly above the same in the top of the casing communicating with the atmosphere and a single valve with a double seat situated between the opening in the wall and the opening above it leading 65 to the air, suitable guideways on the bottom wall of the casing and in the opening in the top wall, the button on the upper end of the rod, the lever pivotally secured and provided with an end spring-finger at one end through 70 which the rod extends and the cam of the motor-spindle resting on and coacting with the outside end of the levers as specified.

CHARLES WARREN.
